A. L. HAMSON

CLOTHES HANGER

Filed Oct. 2, 1923

UNITED STATES PATENT OFFICE.

ARTHUR L. HAMSON, OF LOS ANGELES, CALIFORNIA, ASSIGNOR OF ONE-FOURTH TO
BERNHARD J. LAMPE, OF LOS ANGELES, CALIFORNIA.

CLOTHES HANGER.

Application filed October 2, 1923. Serial No. 666,071.

To all whom it may concern:

Be it known that I, ARTHUR L. HAMSON, a citizen of the United States, and a resident of Los Angeles, county of Los Angeles, State 5 of California, have invented new and useful Improvements in Clothes Hangers, of which the following is a specification.

This invention has to do with a hanger, particularly suited to hold clothes or the 10 like.

It is an object of this invention to provide a device of the character specified which is collapsible and suitable for use in dwellings, or in like situations.

15 Another object of this invention is to provide a compact, simple and convenient device of the character specified.

Another object of this invention is to provide a device of the character specified, which 20 is strong durable and inexpensive to manufacture.

The various objects and features of my invention will be best and more fully understood by reference to the following detailed 25 description of a typical preferred form of the invention, throughout which description reference is had to the accompanying drawings, in which:

Fig. 1 is a view showing my present invention built into a wall;

Fig. 2 shows a face or front view of the invention in a form suitable for mounting on a wall, or the like;

Fig. 3 is a side elevation of the device 35 shown in Fig. 2, being a view taken as indicated by the line 3—3 on Fig. 2;

Fig. 4 is an enlarged detail sectional view, taken as indicated by the line 4—4 on Fig. 2;

Fig. 5 is a view similar to Fig. 4, showing 40 the parts in another position;

Fig. 6 is a detail plan section, taken as indicated by the line 6—6 on Fig. 5; and

Fig. 7 is a view similar to Fig. 6, showing the parts in another position.

45 The device provided by this invention includes, generally, a support or mounting, a body to be carried by the support, and arms carried by the body. The support is subject to variation to conform with the manner in 50 which the device is to be used and to suit various situations. In the drawings I have illustrated two typical forms of support which are most common. In Fig. 1 of the drawings I have illustrated the support

built or embodied in a wall 10 and have 55 illustrated it as including two spaced vertical side parts 11^a extending from a base 13^a. In a situation such as I have illustrated in Fig. 1 the side parts 11^a are preferably set in the wall and in a suitable framing so that 60 the entire device may be covered by a door 12, which, when closed, will be substantially even with the face of the wall.

In Figs. 2 to 7, inclusive, of the drawings I have disclosed a form of support suitable 65 for mounting on a wall or any other suitable carrier. In this form of the invention the side parts 11 of the support are vertically disposed and extend outwardly in the proper spaced relation from a suitable base 13. The 70 base 13 serves to carry and hold the side parts and serves as a part by which the entire device can be mounted.

The body 14 of the device is carried between the side parts 11 of the support and includes a back 15 and two spaced flangelike parts 16 which project from the back. The flanges 16 extend from the back so that they are parallel and spaced apart sufficiently to receive the inner end portions of the arms 17, in the manner hereinafter described. The body 14 extends horizontally between the side parts 11 and is held in place between the side parts by projections 18 which extend from the ends of the body into suitable 80 grooves 19 formed in the inner faces of the side parts 11. In practice the projections may be integral with a part of the body, for instance, one of the flanges, as illustrated in the drawings. The grooves 19 in the two side parts are correspondingly shaped and have vertical parts 20 which hold the projections 18 with the body in position with its back 15 against the base 13 of the support. 90

At the upper ends of the vertical parts 20 the grooves 19 have outwardly extending horizontal parts 21, into which the projections 18 can be moved to allow the body to be rotated or swung from the position where the back 15 engages the base 13 to a position where one of the flanges 16 is at or substantially parallel to the base 13. If so desired the grooves can be extended to the edges of the side parts to allow removal of the projections from the grooves. It will be understood, of course, that the various parts thus far described fit together so that the body can be freely manipulated in the manner 100 105

just described between the two positions illustrated in Figs. 4 and 5.

The arms 17, of which there may be any suitable number, are carried by the body 14 so that they extend outwardly from and in the direction of the flanges 16, and can be folded to lie together side by side or extended so that they are spaced apart in a fan-like formation. The inner end portions of 10 the arms extend between the flanges 16 and are carried on pivot pins 22 which extend between the flanges, as clearly illustrated in Figs. 4 and 5 of the drawings. The pins 22 preferably extend freely through the arms 17 15 and project into the flanges 16. The arms extend somewhat inwardly from the pivot pins 22 to have parts 23 which cooperate to limit the spreading of the arms. The parts 23 inward of the pins 22 may be tapered or shaped in the manner illustrated in Figs. 6 20 and 7 of the drawings, so that they lie close together when the arms are spread, so that they limit the spreading between adjacent arms, and so that they engage one another 25 so that the arms can be substantially uniformly spaced, as I have illustrated in Fig. 7 by operating only the innermost arms. The outer portions of the arms may be any suitable length and may be finished so that 30 they are neat and sightly.

When the device is not in use the arms 17 may be folded together, as illustrated in Figs. 1, 2, 3, and 6 of the drawings, and the body may be positioned so that one of its 35 flanges 16 lies close to the base 13 with the arms 17 projecting downwardly. When it is desired to put the device in position for operation the body 14 may be swung so that the flanges 16 are in a horizontal position 40 whereupon the body can be moved rearwardly and lowered so that the pins 18 are carried in the vertical parts of the grooves with the back 15 engaging the base 13. With the body in this position the arms can be spread 45 in the desired manner to hold whatever objects may be desired.

It will be apparent from the foregoing description and from examination of the drawings that the device of the present invention is extremely simple, compact and inexpensive of manufacture. The device may be designed and proportioned to suit various conditions and so that it is particularly strong and rigid. It is to be particularly noted that the device embodies no intricate parts such as are liable to get out of order and that it can be manipulated very easily and quickly.

Having described only a typical preferred form of my invention I do not wish to limit myself to the specific details hereinabove set forth but wish to reserve to myself any changes or variations that may appear to those skilled in the art or fall within the 65 scope of the following claims.

Having described my invention, I claim:

1. A device of the character described including a body, and a plurality of arms pivotally connected with the body to project outwardly therefrom and so that they have parts extending inwardly to cooperate to limit movement between adjacent arms.

2. In combination, a support having two spaced side parts, a body, a plurality of arms pivotally carried by the body so that they can be folded together or spread apart, and means for holding the body between the side parts so that it is movable between a position where the arms extend downwardly and a position where the arms project outwardly.

3. In combination, a support having two spaced side parts, a body having two spaced flanges, a plurality of arms extending between the flanges and pivotally connected therewith so that they can be folded together or spread apart, and means for holding the body between the side parts so that it is movable between a position where the arms extend downwardly and a position where the arms project outwardly.

4. In combination, a support having two spaced side parts, a body, a plurality of arms pivotally carried by the body so that they can be folded together or spread apart, and means for holding the body between the side parts so that it is movable between a position where the arms extend downwardly and a position where the arms project outwardly, and means for limiting the spreading between adjacent arms.

5. In combination, a support including a base and two spaced side parts extending from the base, a body, arms carried by the body to extend therefrom, and means for holding the body between the side parts including grooves in the side parts and projections on the ends of the body extending into the grooves, the grooves having parts to hold the projections with the body bearing against the base and the arms projecting outwardly and parts continuous with the first mentioned parts to hold the body with the arms extending downwardly.

6. In combination, a support including a base and two vertical spaced side parts projecting outwardly from the base, a body including a back and two spaced flanges extending from the back, arms extending between the flanges, pins pivotally holding the arms between the flanges so that they have parts extending inwardly from the pins, and means for holding the body between the side parts including grooves in the side parts and projections on the ends of the body extending into the grooves, the grooves having vertical parts to hold the projections with the back of the body engaging the base and the arms extending outwardly and horizontal parts extending outwardly from the upper

ends of the vertical parts to hold the projections with the body in position where the arms extend downwardly.

7. In combination, a support including a base and two spaced side parts extending from the base, a body, arms carried by the body to extend therefrom, and means for holding the body between the side parts including grooves in the side parts and projections on the body extending into the grooves, the grooves having vertical parts to hold the projections with the body bearing against the base and the arms projecting outwardly, and horizontal parts extending outwardly from the upper ends of the vertical parts to hold the body with the arms extending downwardly.

8. A device of the character described including, a body, a plurality of arms pivotally connected with the body so that they can be folded together or spread apart, and a pivotal mounting for the body whereby

it is movable between a position where the arms extend horizontally, and a position where the arms extend vertically.

9. A device of the character described including, a body, a plurality of arms pivotally connected with the body so that they can be folded together or spread apart, a pivotal mounting for the body whereby it is movable between a position where the arms extend horizontally, and a position where the arms extend vertically, and means whereby the arms are held against downward movement when in the horizontal position.

In witness that I claim the foregoing I have hereunto subscribed my name this 21st day of September, 1923.

ARTHUR L. HAMSON.
